UNITED STATES PATENT OFFICE.

KARL A. SIMMON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,416,076.

Specification of Letters Patent. Patented May 16, 1922.

Application filed February 13, 1920. Serial No. 358,550.

To all whom it may concern:

Be it known that I, KARL A. SIMMON, a citizen of the United States, and a resident of Edgewood Park, in the county of Allegheny and State of Pennsylvania, have invented a new and useful Improvement in Systems of Control, of which the following is a specification.

My invention relates to systems of control and particularly to the control of so-called "safety" or "quick-service" cars for operation thereof from a distance when running over railroad crossings and the like.

In my copending application, Serial No. 196,395, filed October 13, 1917, is illustrated and described a system whereby, upon approaching a railroad crossing, the car operator may dismount and carry a small push-button switching device to the far side of the crossing. Upon manipulation of the push-button device, the car is caused to run over the railroad crossing under the control of the operator who thus has a clear view of the tracks during the period that he is effecting the travel of the car from the one to the other side of the railroad crossing.

My present invention aims to improve upon the previous system by providing means for ensuring that the vehicle will not be left standing upon the railroad crossing in the event of sudden incapacitation of, or accident to, the operator when he is controlling the car from a distance, as described above.

More specifically stated, it is the object of my invention to provide, in combination with the control system outlined above, a time-element mechanism whereby, when once the vehicle has been set into motion to effect crossing of the railroad tracks, such motion will be continued, irrespective of disability of the operator, for a predetermined distance that is sufficient to ensure that the car fully clears the railroad crossing.

Another object of my invention is to provide means under the control of the operator when occupying a station on the opposite side of the railroad crossing from the car, whereby, if desired, he may render the time-element mechanism inoperative and manually control the car to stop the motion thereof or to again effect forward movement of the car.

My invention may best be understood by reference to the accompanying drawings, wherein

Figure 1 is a view, in elevation, of a safety car and its operator under the conditions of remote control that are noted above;

Fig. 2 is a diagrammatic view of the main circuits included in a system of control that may be installed upon the safety car;

Fig. 3 is a diagrammatic view of the normal and emergency auxiliary circuits for governing the operation of the main system that is shown in Fig. 2; and

Fig. 4 is a view, partially in elevation and partially in section, of an auxiliary control apparatus embodying certain principles of my present invention.

Referring to Fig. 1, the view illustrates a safety or quick-service car 1 that is supplied with energy from a trolley and grounded rails 2 in accordance with a familiar practice. The vehicle is shown as located on one side of a steam railroad crossing or the like including tracks 3 and 4, while the single car operator 5 is situated on the remote side of the railroad crossing. The operator holds in one hand a push-button device 6 that is electrically connected, through a flexible cable 7, to the control apparatus on the vehicle 1, as subsequently more fully described, to effect remote control of the vehicle and cause it to safely cross the railroad crossing.

Referring to Fig. 2 of the drawings, the system shown comprises supply-circuit conductors Trolley and Ground; a plurality of main driving motors respectively having commutator-type armatures A¹ and A² and field windings F¹ and F² of the series type; a reversing switch RS, preferably of a familiar electrically-controlled type, as indicated in Fig. 3, but here conventionally shown, for the sake of simplicity and clearness, a line switch LS; a current-limit switch L; an accelerating resistor 11; and a drum controller 12 having an actuating mechanism 13 for governing the acceleration of the driving motors by suitably varying the resistor 11 and by changing over the motor connections from series to parallel relation, in accordance with the familiar "shunting" type of transition. However, since the particular main-circuit connections are immaterial to my present invention, which is capable of application to any well-known

motor-operating system, no further description thereof is deemed necessary, with the exception of describing the actuating mechanism 13, which is preferably, but not necessarily, employed in connection with my invention.

The actuating mechanism 13 is of a familiar electrically-controlled, pneumatically-operated type, comprising a pinion 15, which 10 is secured to the operating shaft 16 for the drum controller 12 and is adapted to mesh with a horizontally-movable rack member 17, the opposite ends of which constitute pistons 18 and 19 that travel within appropriate operating cylinders 20 and 21, respectively. A normally open valve 22, having an actuating coil "Off," communicates with the outer end of the cylinder 20, while a normally closed valve 23, having an actuating 20 coil "On," is associated with the outer end of the other cylinder 21. Fluid, under pressure from any suitable source (not shown), may be conveyed to the valves 22 and 23, whereby the apparatus is normally biased to 25 the illustrated extreme position.

The mechanical operation of the actuating mechanism 13 may be set forth as follows:

Upon concurrent energization of the actuating coils On and Off, the initial unbalanced fluid-pressure conditions in the apparatus are reversed; that is, fluid, under pressure, is admitted to the cylinder 21 through the valve 23 and fluid is exhausted from the other cylinder 20 through the valve 35 22 to the atmosphere. Consequently, a movement of the pistons 18 and 19 and of the controller 12, towards the right in the illustrated case, ensues. To arrest such movement at any time, it is merely necessary to de-energize the off coil, whereupon balanced high-pressure conditions obtain in the mechanism, and a positive and reliable stoppage thereof is effected.

To produce a return movement of the device, the actuating coils On and Off are concurrently de-energized, whereupon fluid-pressure conditions revert to the original state and the desired backward movement is effected.

50 Referring now to Fig. 3, the auxiliary system shown employs the supply-circuit conductors Trolley and Ground, a suitably reduced control voltage being obtained through the agency of a control resistor 25, in accordance with a familiar practice. The system further comprises the actuating coils for the line switch LS, for the actuating mechanism 13 and for the reversing switch RS, together with suitable electrical interlocks of a familiar type; an auxiliary resistor 26, a brake-controlling coil marked "Brake"; and a battery B for energizing such coil under predetermined conditions to be set forth, to release the brake application; a master controller MC and a master

reverser MR for primarily governing the operation of the system; a time-element device 27 and my portable switching device 6 of the well-known multiple push-button type.

70 One form of apparatus embodying the principles of my invention is shown in Fig. 4 in conjunction with the switching device 6, which comprises a suitable shell or enclosing member 30 and a plurality of push-buttons 31, 32 and 33 the latter two of which are normally held in their outer or open-circuit position by suitable springs, as illustrated in Fig. 3. A retrieving mechanism 34, represented by the coiled cable in Fig. 80 3, and shown in section in Fig. 4, comprises a rotatable drum or hollow spool having end-plates 42, a multi-conductor cable 43 being wound upon the cylindrical body portion of the spool. A plurality of externally 85 grooved hubs 44 and 45 are secured to the outer faces of the respective end-plates 42 for performing the double function of aiding to support the retriever drum upon a centrally-located stationary shaft 46 and to 90 carry an electrical interlocking plate 40, as hereinafter more fully set forth.

95 One end 47 of the stationary shaft 46 is threaded to permit axial movement of the retriever drum towards the left as the flexible cable 43 is paid out, and a torsion spring 48 is located within the drum, having its respective ends secured to the shaft 46 and to the left-hand end-plate 42, for the purpose of automatically retrieving the cable 43 or 100 maintaining it taut under all operating conditions.

105 For the purpose of maintaining the desired electrical connections of the several conductors forming the cable 43 during rotative movement of the retriever drum, a plurality of collector rings or bands 49 surround the drum, being connected to the respective cable-conductors in any suitable manner.

110 The interlocking plate 40 comprises a slab or base 50 of insulating material upon which are mounted a plurality of contact strips or blocks 51, 52 and 53 that respectively engage pairs of stationary control fingers 55, 115 56 and 57 in predetermined positions of the retrieving device, such control fingers being preferably mounted upon a finger-base 54 of a familiar type, for effecting the desired external-circuit connections that are shown 120 in Fig. 3. A further set 58 of control fingers is mounted upon the slab 50 or an extension thereof for engaging the band or ring contact members 49 of the drum. A suitable cable 59 is provided for connecting the control fingers 58 to a plurality of terminals or binding posts 60 that are located upon the finger-base 54, whereby the external circuit connections that are shown in Fig. 3 may be readily made.

The interlocking plate 40 is adapted to move longitudinally in accordance with the concurrent rotative and axial movement of the retriever drum, such action being effected by reason of mounting the interlocking plate upon a plurality of arms 61 and 62 that terminate in bands or rings loosely fitting within the grooves around the drum hubs 44 and 45, respectively.

10 A latching device 41 for the retrieving apparatus comprises an intermediately pivoted bar or rod 65, one end of which is provided with a latch or lock 66 to suitably engage the right-hand end-plate 42, whereby movement of the retriever drum in either a rotative or an axial direction is prevented. The other end of the rod 65 has mounted upon it a half drum 67, or the equivalent, which carries a plurality of contact segments 15 68 and 69 for engaging suitable control fingers 70 in accordance with the position of the latching device, as hereinafter described in detail in connection with Fig. 3. The latching device 41 is adapted to occupy a 20 position marked "Unlatched" as well as the illustrated position designated as "Latched".

The familiar operating handle or lever 71 of the master reverser MR is preferably employed for manually actuating the interlocking device from the one to the other of its positions, whereby it is necessary for the vehicle operator, after stopping the car near a railroad crossing, to actuate his master reverser to the "off" position, remove the 25 operating handle 71 and apply it to the interlocking device 41, before the retrieving mechanism can become operative for the intended purpose. In this way, the normal operation of the driving motors from the vehicle platform is prevented during the time 30 that the operator is controlling the vehicle from a distant point by means of the external control apparatus.

It will be understood that the entire apparatus of Fig. 4 may be appropriately mounted in any convenient location within the car vestibule, which need not be set forth here.

The time-element mechanism 27 may be of 45 any familiar form and is here shown as comprising a movable plate or control board 72 which may be actuated through the agency of a pneumatic device 73 comprising a piston 73a operating within a cylinder 73b and biased to the illustrated lowermost position by means of a coil spring 73c. A small vent or exhaust port 73d is provided in the lower end of the cylinder 73b.

An electrically-controlled valve 74 is supplied with fluid under pressure from an inlet pipe or passage 74a which is connected to any suitable source of fluid under pressure (not shown), and an actuating coil 74b, when energized, serves to effect communication be- 50 tween the pipe 74a and the cylinder 73b.

The mechanical operation of the time-element relay may be set forth as follows. Whenever the actuating coil 74b is energized, fluid under pressure is admitted to the operating cylinder 73b, whereupon the piston 73a is actuated to its uppermost position in opposition to the action of the biasing spring 73 and, consequently, the control board 72 is actuated from its normal position *a* to its extreme operative position *b*. As soon as 75 the actuating coil 74b is de-energized, the fluid under pressure in the cylinder 73b gradually leaks out through the vent 73d at a predetermined rate dependent upon the size of the vent, as will be understood. Consequently, a predetermined time period is required for the control board 72 to return to its normal position *a* from its position *b*, and it should be observed that the operation of the time-element relay is brought about 80 through the agency of only a momentary energization of the actuating coil 74b, such as is provided by the normally open push-button 33 of the switching device 6.

It will be appreciated that the illustrated 85 form of time-element device is not essential to my present invention and that a clock-work mechanism or other time-element mechanism may be substituted for the illustrated apparatus 27 to provide a certain 90 time-element control of the circuits that are governed by the control board 72, as herein-after more fully set forth.

Moreover, if desired, the operation of the control board 72 may be made dependent 95 upon the number of revolutions of the car axles, as will be understood, whereby the same result of ensuring a given travel of the car may be obtained.

To effect normal acceleration of the driving motors, the master reverser MR is moved to its "forward" position, for example, and the master controller is actuated to its operative position *a*. A circuit is thereby established from the positive terminal of the 100 battery B through the "brake" coil, conductors 110 and 110a, contact segment 108 of the master reverser and conductor 111 to ground, whence circuit is completed to the negative battery terminal. In this way, the 105 illustrated vehicle-braking system is rendered inoperative during normal car operation, with the master reverser occupying an operative position.

Another auxiliary circuit is established 110 from the trolley through conductor 165, control fingers 166 and 167, which are bridged by contact segment 168 of the master controller, and thence, through control resistor 115 25, to ground.

A further circuit is established from an intermediate tap-point 169 of the control resistor through contact strip 51 of the interlocking plate 40 (Fig. 4), contact segment 68 of the latching device 41, when occupy- 120 125 130

ing its illustrated "latched" position, conductors 80 and 81, the actuating coil of the switch LS, contact segment 82 of the main controller 12 in its initial position, contact segment 83 of the main reversing switch RS in its "forward" position, conductors 84 and 85, contact segment 86 of the master reverser in its "forward" position, conductor 87, control fingers 88 and 89, which are bridged by contact segment 90 of the master controller, and conductor 91 to ground.

As soon as the line switch LS has closed to connect the driving motors to the supply circuit, a holding circuit for the actuating coil of the switch is formed by the bridging of the contact segment 82 by an interlock LS-in.

Since the relation of the forward and reverse coils for the main reverser RS to the remainder of the system is familiar to those skilled in the art, and, furthermore, has no bearing upon the present invention, it is deemed unnecessary to describe such circuits in detail.

25 A further auxiliary circuit is established, upon the closure of the line switch LS, from a second intermediate point 92 of the control resistor 25 through the actuating coil On and an interlock LS-in to another intermediate tap-point 93 of lower voltage. However, no movement of the main controller 12 occurs until the off coil is energized, which takes place whenever the limit switch L occupies its lower position by the completion 30 of another circuit from the tap-point 92 through the actuating coil Off, contact disk 95 of the limit switch L and interlock LS-in to the tap-point 93. In this way, the main controller 12 is actuated through its various 35 positions, in accordance with the movements of the limit switch L, to suitably manipulate the variable resistor 11 and to change over the driving motor connections from series to parallel relation, as will be understood.

40 To effect the external control of the vehicle when a railroad crossing or the like is approached, the vehicle is stopped on the near side of the crossing, and the master reverser MR is manipulated by the usual operating handle 71 to the "off" position, which does not operate the main reversing switch RS, but, upon removal of the operating handle 71, control of the motor operating system by the master controller is prevented by reason of the familiar mechanical interlocking device (not shown) that is provided in all modern types of control apparatus.

45 Furthermore, the vehicle brakes are automatically applied, as soon as the master reverser occupies its "off" position, by reason of the interruption of the previously-traced circuit through the "brake" coil.

50 The master-reverser operating handle 71

is then applied to the latching device 41 (Fig. 4) which is thereby actuated to its "unlatched" position. The motorman may then take the push-button switching device 6 and cross the railroad tracks, as illustrated in Fig. 1, the flexible cable 43 in the meanwhile being paid out as necessary by reason of the helical movement of the retriever drum along the threaded shaft 46, in opposition to the action of the coil spring 48. 75 Such movement of the retrieving device interrupts the auxiliary circuits including contact block 51 and closes new auxiliary circuits including contact blocks 52 and 53, of the interlocking plate 40.

Consequently, by pressing the push-button 32 of the switching device 6, the following circuit through the actuating coil "Brake" is energized and the braking system is rendered inoperative: from the lower terminal of the "brake" coil through conductor 110, push-button 32, conductor 115, contact segment 116 of the time-element device 27 in its normal position *a* and conductor 117 to ground.

90 In this way, the vehicle brakes are released and operation of the vehicle may then be effected by depressing the push-button 33, whereupon a new circuit is established from the positively-energized conductor 80, through conductor 81, actuating coil of the line switch LS, contact segment 82 of the main controller 12 in its initial position, contact segment 83 of the main reversing switch RS in its "forward" position, conductors 84 and 118, push-button 33, conductor 119, brake-release interlock 119*a*, thereby ensuring that the vehicle brakes are not set, and conductor 119*b* to ground. In this way, the line switch LS is closed to effect the connection of the propelling motors to the supply circuit, whereupon the vehicle starts into motion and begins to cross the railroad tracks.

100 At the same time, the closure of the push-button 33 completes another circuit from the positively-energized conductor 80 through conductor 121, actuating coil 74*b* of the time-element device 27, conductor 120, push-button 33, and conductor 119 to ground. In 105 this way, the time-element mechanism 27 is immediately actuated to its final operative position *b*, as previously described, and, upon the release of the push-button 33, the gradual return movement takes place in the 110 manner already set forth.

As soon as the time-element relay has moved from its normal position *a*, a new circuit is established from the lower terminal of the brake coil through contact segment 53 on the interlocking plate 40 of the retrieving mechanism, conductor 122, normally-closed push-button 31, conductor 123, contact segment 124 of the time-element relay and conductors 125 and 117 to ground. 130

The brake coil is thus kept energized, irrespective of the interruption of the previously-traced circuit including contact segment 116 of the time-element relay, to hold off the vehicle brakes as long as the electrical control of the vehicle is occurring.

Furthermore, to ensure the closure of the line switch LS, even though the push-button 33 is accidentally or intentionally released, a new circuit is established, as soon as the time-element relay has been actuated, as described above, from the positive terminal of the battery B through conductor 132, holding coil 24 of the line switch LS, conductors 133 and 122, push-button 31, conductors 123 and 134a, contact segment 134 of the time-element relay and conductors 135 and 117 to ground.

Consequently, after the push-button 33 has once been depressed and is then released for any reason, the line switch coil is maintained energized for a predetermined length of time, namely, the period consumed by the return movement of the time-element relay 27. Therefore, the car-propelling motors are energized for a sufficient length of time to ensure that the vehicle safely crosses the railroad crossing, irrespective of the fact that, after the motorman has inaugurated the movement of the vehicle, he becomes negligent or is incapacitated by an accident. In this way, the vehicle is positively prevented from being stalled on the railroad tracks.

Although the line switch LS is thus closed to reconnect the driving motors to the supply circuit, the actuating coils On and Off for the main controller 12 are not energized in the previously-described manner, by reason of the master controller MC occupying its "off" position. It will be understood, however, that if desired, the actuating coils On and Off may readily be reconnected by further contacts on the latching device 41 to be operative during the period of external vehicle control also.

When the vehicle has passed the railroad crossing and has approached to within a short distance of the operator, if the time-element relay 27 has not returned to its normal position *a* to effect opening of the line-switch coil circuit and setting of the vehicle brakes, such operation may be effected by depressing the push-button 31 to interrupt the energization of the common conductor 123, whereby the brake coil is de-energized to cause the application of the vehicle brakes and, at substantially the same time, the holding coil 24 for the line switch LS is de-energized to effect the opening of the line switch.

When the portable switching device 6 has been returned to its normal position, the master reverser operating handle 71 may be utilized to return the latching device 31 to its illustrated "latched" position to prevent further actuation of the retrieving device,

and the operating handle 71 may then be reinserted in the master reverser to actuate it to the one or the other of its operative positions. Actuation of the master controller MC to govern the system in the previously-described normal manner is thus again permitted, and the braking system is again rendered inoperative by reason of the previously-described energizing circuit through the "brake" coil whenever the master reverser occupies an operative position.

It will be understood by those skilled in the art that, in the case of a plurality of motor-driven vehicles operating on the familiar multiple-unit principles, my invention may be readily applied to the external control of such a train through the agency of the usual train-line conductors.

I do not wish to be restricted to the specific circuit connections, structural details or arrangement of parts herein set forth, as various modifications thereof may be effected without departing from the spirit and scope of my invention. I desire, therefore, that only such limitations shall be imposed as are indicated in the appended claims.

I claim as my invention:

1. In a system of vehicle control, the combination with an electric motor and means located upon the vehicle for normally governing the motor operation, of means for effecting motor operation from a point external to the vehicle, for insuring such operation for a predetermined period and for preventing concurrent operation from the vehicle itself.

2. In a system of vehicle control, the combination with an electric motor and an operating system therefor, of means located upon the vehicle for normally governing said system, and means including flexible conductors for controlling the system from selected points external to the vehicle and for retrieving or paying out said flexible conductors as the vehicle moves in the one or the other direction, and means for automatically maintaining such external control for a given length of time.

3. In a system of vehicle control, the combination with an electric motor and an operating system therefor, of means, including a removable operating handle, located upon the vehicle for normally governing said system, and means, including said handle in a different location, for controlling the system from a point external to the vehicle and for maintaining such control for a pre-selected period.

4. In a system of vehicle control, the combination with an electric motor and an operating system therefor, of means, including a reverser having a removable operating handle, located upon the vehicle for normally governing said system, and means, including said handle in a different location after the

- reverser occupies a predetermined position, for controlling the system from a point external to the vehicle and for insuring such control over a given period.

5. In a system of vehicle control, the combination with an electric motor and an operating system therefor, of means, including a reverser having a removable operating handle, located upon the vehicle for normally governing said system, and means, including said handle in a different location after the reverser occupies its "off" position, for controlling the system from a point external to the vehicle and for automatically maintaining such control for a predetermined period.

6. In a system of vehicle control, the combination with an electric motor and an operating system therefor, of means, including a reverser having a removable operating handle, located upon the vehicle for normally governing said system, means, including said handle in a different location and including flexible conductors, for controlling the system from selected points external to the vehicle and for retrieving or paying out said flexible conductors as the vehicle moves in the one or the other direction, and time-element means for automatically continuing such control for a given length of time.

7. In a system of vehicle control, the combination with an electric motor and an operating system therefor, of means located upon the vehicle for normally governing said system, a braking system, and means, including a portable switching device, for controlling said operating system from a point external to the vehicle for a predetermined period and for automatically rendering said braking system operative whenever certain circuits of said switching device are de-energized.

8. In a system of vehicle control, the combination with an electric motor and an operating system therefor, of means located upon the vehicle for normally governing said system, a braking system, and means for controlling said operating system from a point external to the vehicle for a given length of time and for automatically rendering said braking system operative when said external governing means is returned to its normal location upon the vehicle.

9. In a system of vehicle control, the combination with an electric motor and an operating system therefor, of means located upon the vehicle for normally governing said system, a braking system, and means, including a portable switching device, normally biased to open-circuit condition, for controlling said operating system from a point external to the vehicle for a predetermined period and for automatically rendering said braking system operative whenever said switching device occupies its biased position and whenever the device is returned to its normal location upon the vehicle.

10. In a system of vehicle control, the combination with an electric motor and an operating system therefor, of means, including a reverser having a removable operating handle, located upon the vehicle for normally governing said system, a braking system, and means including said handle in a different location and including flexible conductors for controlling the system from selected points external to the vehicle for a certain length of time and for retrieving or paying out said flexible conductors as the vehicle moves in the one or the other direction, said external governing means also including a portable switching device for automatically rendering said braking system operative when said flexible conductors are completely retrieved.

11. In a system of vehicle control, the combination with an electric motor and an operating system therefor, of means, including a reverser having a removable operating handle, located upon the vehicle for normally governing said system, a braking system, and means, including said handle in a different location after the reverser occupies its "off" position, for controlling the system from a point external to the vehicle for a predetermined period, said external governing means also including a portable switching device for automatically rendering said braking system operative whenever certain circuits of said switching device are de-energized while said reverser occupies its "off" position.

12. In a system of vehicle control, the combination with a supply circuit, an electric motor, and means located upon the vehicle for normally governing the motor operation, of means normally carried upon the vehicle for controlling motor operation from said supply circuit externally to the vehicle, and means operative with said last means for insuring a certain period of such control.

13. In a system of vehicle control, the combination with a substantially constant-voltage supply circuit, an electric motor, and means located upon the vehicle for normally governing the motor operation, of portable means directly utilizing said supply circuit for controlling motor operation externally to the vehicle for a given length of time.

14. In a system of vehicle control, the combination with a direct-current supply circuit comprising "trolley" and "ground" conductors, an electric motor, and means located upon the vehicle for normally governing the motor operation, of independent means for effecting motor operation by energy derived from said conductors, said independent means embodying control means operable from points external to the vehicle, and time-element means for maintaining a predetermined period of such external control.

15. In a system of vehicle control, the combination with a propelling motor, of portable means for governing said motor to effect relative travel of the vehicle and the operator for a predetermined period. 50
16. In a system of vehicle control, the combination with a propelling motor and means located upon the vehicle for normally governing the vehicle operation, of means for rendering said normal control inoperative and for effecting relative travel of the vehicle and the operator for a given length of time. 55
17. In a system of vehicle control, the combination with an electric motor and means located upon the vehicle for normally governing the motor operation, of a brake, and single means external to the vehicle for controlling both the motor and the brake 60 and for effecting such control within a certain time limit.
18. In a system of vehicle control, the combination with a propelling motor and means located upon the vehicle for normally governing the vehicle operation, of a brake, means adapted to be carried externally to the vehicle for releasing said brake and energizing the motor, and time-element means for maintaining such external control for a 65 predetermined period.
19. In a system of control, the combination with an electric motor and control means for effecting normal operation of the motor to a predetermined stage, of other control means for effecting motor operation to a 70 different stage and for a certain period.
20. In a system of vehicle control, the combination with a propelling motor and control means located upon the vehicle for effecting normal operation of the motor to full speed, of portable control means for effecting slow-speed motor operation for a given length of time. 75
21. In a system of vehicle control, the combination with a propelling motor, of means external to the vehicle for controlling said motor, and means for automatically maintaining such control for a limited period after the inauguration thereof. 80
22. The combination with an electric vehicle, of external means for controlling the operation of the vehicle, and means for insuring movement of the vehicle for a certain distance. 85
23. The combination with an electric vehicle, of external means for inaugurating movement of the vehicle, and means for then maintaining movement of the vehicle for a given distance. 90
24. In a system of vehicle control, the combination with an electric motor and an operating system therefor, of means located upon the vehicle for normally governing said system, a braking system, means, including a portable switching device, for controlling said operating system from a point external to the vehicle, time-element means for continuing such control for a predetermined period, means responsive to a certain operation of said portable device for initially releasing said braking system under conditions of external control, and means dependent upon the movement of said time-element means for maintaining such release unless a different operation of said portable device occurs. 95
25. In a system of vehicle control, the combination with a supply circuit, an electric motor, a line switch therefor, and means located upon the vehicle for normally governing said line switch to effect the motor operation, of portable means normally carried upon the vehicle for controlling said line switch to effect motor operation from said supply circuit external to the vehicle, time-element means initially governed by certain manipulation of said portable means for maintaining such control for a predetermined period, a source of energy, and means dependent upon the movement of said time-element means for maintaining the closure of said line switch from said source independently of such initial manipulation of said portable means. 100

In testimony whereof, I have hereunto subscribed my name this 30th day of January, 1920.

KARL A. SIMMON.
